UNITED STATES PATENT OFFICE.

THEODORE WEINSHANK AND SIDNEY E. FENSTERMAKER, OF INDIANAPOLIS,
INDIANA.

SECTIONAL ADJUSTABLE VENTILATOR-CASING.

1,265,013.

Specification of Letters Patent.

Patented May 7, 1918.

Application filed December 11, 1915. Serial No. 66,362.

To all whom it may concern:

Be it known that we, THEODORE WEINSHANK and SIDNEY E. FENSTERMAKER, citizens of the United States, residing at Indianapolis, in the county of Marion and State of Indiana, have invented a new and useful Sectional Adjustable Ventilator-Casing, of which the following is a specification, reference being had to the accompanying drawings and to the letters and figures of reference marked thereon.

This invention relates to the ventilation of rooms or apartments of buildings and has reference more particularly to the control of the admission of fresh air and also to the heating or re-heating of the air for ventilating purposes, more particularly when the heating of the room or apartment is accomplished by means of radiators heated by steam or hot water.

An object of the invention is to provide improved construction in ventilator base boxes and inclosures for heat radiators that shall simplify the work and reduce the cost to the minimum in their application to the radiators. Another object is to provide an improved ventilator wall-box and also an improved air-duct for connecting the base box of the radiator with the wall-box in order to obviate the necessity for cutting and fitting different parts when making the connections between the base box and the wall-box. A further object is to provide an improved base box and radiator inclosure that may be set up in proper place without it being necessary to lift and carry the radiator and place it onto the base box, an object being to provide a convenient indicator for the ventilator apparatus, and a more specific object is to provide an improved sectional ventilator structure that shall be adjustable to the size of the radiator, in order to avoid the labor and expense incidental to hand-fitting when installing or repairing the ventilating or the heating appliances.

With the above-mentioned and other objects in view, the invention consists in a sectional ventilator base box of improved construction for connection with a radiator and provided with an improved intake duct, an improved sectional wall box with which the duct is adjustably connected, an improved radiator inclosure adapted to be readily connected with the base box so as to inclose a portion of the radiator, and

an improved ventilator indicator; the invention consisting further in the novel parts, and combinations and arrangements of parts, as hereinafter particularly described and further defined in the accompanying claims.

Referring to the drawings,—Figure 1 is a fragmentary section of a building wall and floor with which a radiator and the improved ventilating appliances are arranged; Fig. 2 is a fragmentary section approximately on the line A—A on Fig. 1 with a front elevation of the radiator partially broken away; Fig. 3 is a perspective view of one of the parts of the improved wall box; Fig. 4 is a fragmentary horizontal section approximately on the line B B on Fig. 1; Fig. 5 is a perspective view of the front wall plate of the base box; Fig. 6 is a perspective view of the rear wall plate of the base box; Fig. 7 is a fragmentary front elevation of the radiator inclosure as preferably constructed; Fig. 8 is a perspective view of the improved base box and the improved air-duct connected thereto minus the dampers thereof; Fig. 9 is a rear perspective view of the improved radiator inclosure partially broken away; Fig. 10 is a front view of the ventilator indicator; Fig. 11 is an end elevation of the base box; Fig. 12 is a perspective view of the improved wall box partially broken away, minus the accessories thereof; Fig. 13 is a fragmentary elevation of the inner side of the front wall of the base box; and, Fig. 14 is a fragmentary horizontal section of the radiator inclosure and the ventilator indicator.

Similar reference characters on the different figures of the drawings indicate corresponding elements or features of construction herein referred to.

In the drawings the numeral 1 indicates the wall of a building and 2 the floor of a room or apartment, the wall having an aperture 3 therein adjacent to the floor, being in many cases below a window at which a radiator is appropriately placed on the floor. The radiator comprises a suitable number of sections 4 connected together, the opposite sides of each section having joint bosses 5 and 5' respectively, as will be understood, and the end or terminal sections of the radiator are provided with supporting legs 6 and 7 respectively that rest upon the floor. The complete radiator, as will be under-

stood, is very heavy, being composed of cast metal.

The improved wall box is composed of cast metal so as to be durable and is inserted 5 in the aperture 3, and it comprises a bottom plate having a flat inner portion 8 and an inclined portion 9 that slants downward toward the front of the wall and has a downwardly extending outer flange 10 and an 10 upwardly extending inner flange 11 thereon; and a top plate comprising a flat inner portion 12 and an inclined outer portion 13 extending upward toward the outer face of the wall and having an upwardly extending 15 outer flange 14 and a downwardly extending flange 15; said plates being connected to suitable end walls. The bottom and top plates are of proper length to conform to the pre-arranged plans, in some cases being 20 longer or shorter than in other cases. The ends of the flat portion of each plate are provided with projecting ears 16 and 17. An end wall plate 18 is provided which is placed between the bottom and top plates 25 at one end thereof and it has an outwardly extending flange 19 and an inwardly extending flange 20, the inner side of the wall plate having a suitable number of inclined ledges 21 thereon behind the flange 20. An 30 other end wall plate 22 is placed between the bottom and top plates at the opposite end thereof and it has an outwardly extending flange 23 and an inwardly extending flange 24, the inner side of the end wall plate having inclined ledges 25 thereon behind the flange 24. The end walls have each a pair 35 of outwardly extending ears 26 and 27 thereon that have contact with the adjacent ears of the bottom and top plates and are connected thereto by means of suitable devices 28 and 28', such as bolts or rivets. The end walls are of suitable height to conform to the prearranged plans, in some 40 cases being greater or less in height than others. It will thus be seen that by selecting bottom and top plates and end walls from the stock on hand a wall box of the required dimensions may be readily built up, and in case of accidental fracture of one 45 of the sections of the wall box it may readily be replaced by a new section without discarding and losing a whole wall box. The outer flanges of the different parts or sections of the wall box, being joined together, 50 form a complete external flange that is placed against the outer face of the building wall and closes the aperture 3. A suitable number of deflectors 29 are placed upon the ledges 21 and 25 behind a screen 30 which 55 is placed behind a continuous inner flange formed by the inner flanges of the different sections of the box.

The base box is also composed of cast metal sections or parts so that it may be 60 readily built up of sections or parts of suit-

able dimensions selected from stock parts, in some cases the box being longer or shorter than in others. The base box comprises a back wall plate 31 having a large aperture 32 therein, the outer side of the plate having a flange 33 thereon that extends around the aperture, the normal inner side of the plate having ears 34, 35, 36, 37 thereon, there being two ears at a short distance from each end of the plate. An air-duct is composed 75 of sheet metal and comprises a bottom 38, a top 39, and end walls 40 and 41 connected to the bottom and the top, one open end of the air-duct being inserted in and secured to the flange 33 by means of bolts 42 or 80 similar devices. The opposite open end of the air-duct is adapted to be inserted adjustably into the wall box so as to practically become an extensible portion thereof, and to this end the bottom 38 has an outwardly extending resilient lip 43, the top having a similar lip 44, the end walls having similar lips 45 and 46 respectively that are sprung into contact with the several portions of the wall box. The rear wall 85 plate of the base box thus may be readily located more or less closely to the inner side of the building wall to conform to the position of the radiator. The upper portion of the opposite ends of the wall plate 31 90 preferably are recessed to form upward facing shoulders 47 and 48 on opposite ends respectively of the plate.

Each of the opposite ends of the base box is composed of two sections, the end walls 100 thus comprising two rear sections 49 and 50 that are placed on the outer side of the ears that are on the respective end portions of the rear wall plate 31 and secured to the ears by means of bolts 51 and 51', the sections 105 extending forward from the wall plate. The upper portions of the end sections are recessed so as to form upward facing shoulders 52 and 53 on the exterior of the respective sections and on the plane of the shoulders 47 and 48 respectively. The forward portions of the sections have concave recesses 54 and 55 in the upper portions thereof respectively to receive the rearward portions of the bosses 5 and 5', respectively, of different sections of the radiator behind which the rear wall plate 31 extends, each end wall section extending between two of the radiator sections. The end wall sections have also 110 external ears 56 and 57 thereon below the recesses, respectively. The base box comprises also a front wall plate 58 that has ears 59, 60, 61, 62 on its inner side, there being two ears at a short distance from each end of the plate. The upper portion of the 115 plate is recessed so as to form an upward facing shoulder 63 on its front portion. The remaining end wall sections 64 and 65 are placed against the outer sides of the ears that are on the respective ends of the front 120 plate. The upper portion of the 125 plate is recessed so as to form an upward facing shoulder 63 on its front portion. The remaining end wall sections 64 and 65 are placed against the outer sides of the ears that are on the respective ends of the front 130

plate 58 and secured to the ears by means of bolts 66 and 66', the forward end sections being placed in contact with the rear end sections and being recessed have upward facing shoulders 67 and 68 on the outer side of their upper portions that are on the plane of the shoulders of the rear end sections and the forward wall plate. The forward end sections are placed between sections of the 10 radiator and have concave recesses 69 and 70 in the upper rearward portions thereof that receive the forward portions of the bosses of the radiator sections, the two concave recesses of the adjacent end sections 15 forming a circular aperture that receives one boss. The forward end sections have also ears 71 and 72 on the exterior thereof below the concave recesses that are secured to the ears 56 and 57 respectively by means of bolts 20 73, 73'. The base box, as will be seen, rests upon the floor 2 and extends upward to a plane above the joint bosses of the radiator so as to inclose the lower portions of the desired number of radiator sections.

25 A radiator-inclosure or casing is provided which preferably is composed of galvanized sheet metal and comprises a back wall 74 that is placed behind the radiator and has a recess 75 in its lower portion to receive the 30 flange 33, the back wall having downwardly extending end portions 76 and 77 that extend to the plane of the shoulders 47 and 48 of the rear wall plate 31, the wall 74 being secured to the upward projecting portion of 35 the rear wall 31 by means of bolts 78. The rear wall has rearwardly extending flanges 79 and 80 on the opposite end portions thereof respectively. The inclosure comprises also a front wall 81 and end walls 82 and 83 40 connected thereto, and extending past the plane of the wall 74 to the outer sides of the flanges 79 and 80 to which they are secured by means of bolts 84 and 85, respectively. The front wall 81 is seated on the shoulder 45 63 and secured to the upper portion of the front wall plate 58 by means of bolts 86, the walls 82 and 83 seated upon the shoulders 52 and 53 and secured to the upper portions 50 of the end walls by means of bolts 86', it being understood that the end walls 82 and 83 are readily inserted between the adjacent sections of the radiator above the lower joint bosses thereof. The inclosure extends upward to a suitable height so as to form a flue to conduct the fresh air upward about 55 the radiator sections.

In order to re-heat the cooler air in the room, the front wall plate 58 of the base box has a doorway 87 therein to be closed by a 60 front damper 88 which is mounted on hinges 89 and 89' on the inner side of the wall plate adjacent to the bottom of the doorway, the rear side of the damper having a link 90 pivotally connected thereto. The inner 65 side of the back wall plate 31 is provided

with hinges 91 and 91' adjacent to the bottom of the aperture 32, the hinges supporting a back damper 92 to operate in the intake air-duct for regulating the admission of fresh air, the damper extending upward 70 against stops 93 formed at the top of the aperture 32, so that the damper may entirely close the air-duct. The forward side of the damper has an ear 94 thereon to which a link 95 is pivoted. A fulcrum-arm 96 is secured to the inner side of the rear wall plate 31 below the aperture 32, and a lever 97 is pivotally supported between its ends on the fulcrum arm, the opposite ends of the lever being pivotally connected to the links 90 and 95 respectively, so that when the front damper, which is provided with an operating knob 98, is closed the back damper is opened, the latter being moved to closed position when the front damper is opened, or is partially closed when the front damper is partially opened.

In some cases the front and back of the radiator inclosure are provided with guides 99 and 100 that extend to the radiator to 90 centrally guide the inclosure.

In order that the position of the back damper 92 may be indicated to those interested, and who may not be familiar with the controlling devices of the damper, an improved indicating appliance is provided 95 and preferably is designed to be observed or inspected on the front of the radiator inclosure. Accordingly the front 81 of the inclosure is provided with a sight-opening 100 101, behind which an indicator plate 102 is arranged and connected by means of a pivot 103 to the inner side of the front 81. The plate 102 has an ear 104 on its free end that is suitable for moving the plate on its pivot, 105 the ear preferably having a hole 105 therein whereby to apply a connecting rod to the ear. The front of the plate has a sign 106, such as "Shut", and another sign 107, such as "Open", thereon, either sign to be 110 brought by movement of the plate to the sight-opening. Preferably the indicator plate is arranged in a guide 108 secured to the inner side of the front 81. The plate 102 may be variously operated and controlled; preferably by means of a wrist pin 109, fixed on one end of the front damper 88, and a connecting rod 110 having an eye 111 that is connected to the pin, the rod being composed of spring-wire so as to be 115 slightly flexible laterally, as it extends through a guide 112 secured to the inner side of the front 81. The rod 110 is suitably connected to the ear 104, preferably adjustably by means of a clamp bolt 113 inserted in the ear 104 and a nut 114 on the bolt at one side of the ear, the bolt having a hole 115 therein to receive the rod 110 for clamping the rod to the opposite side of the ear.

It will be seen from the foregoing that after installing the ventilating appliances, if for any reason it be found desirable to increase or decrease the base box and in-
5 closure capacity the same may be readily accomplished by disconnecting the parts of the same and supplying corresponding parts of different dimensions without disturbing the radiator.

- 10 In practical use the simple adjustment of the front damper 88 effects the control of the back damper 92, so that the admission of air into the room is readily controlled. When the front damper is closed, as in Fig. 15 1, the back damper extends flatwise upon the bottom of the air-duct, so that the full capacity of the latter is available for the admission of fresh air, and when less is desired the air-duct is partially closed automatically on partially opening the front damper or may be entirely closed so as to re-heat the air in the room upon full opening of the front damper. The air rises in the inclosure or flue and becomes heated by 20 the radiator in its passage to the top of the inclosure, the walls of the inclosure becoming heated by the heated air so as to radiate heat. When the front damper is closed and the back damper open the "open" sign 107 25 appears at the sight-opening 101; and when the back damper is closed by the front damper when lowered to open position, the latter pulls down the rod 110 and swings the plate 102 down so that the "shut" sign 106 appears at the sight-opening. 30

Having thus described the invention, what is claimed as new is—

1. A sectional adjustable ventilator casing comprising a wall box, an intake air-
40 duct freely insertible into the inner end of the wall box and having a resilient lip on its end to engage the inside of the wall box, the lip rendering the duct conformable to the cross-sectional dimensions of the box, a base box connected to the air-duct, and a radiator-inclosure on the base box.

2. A sectional adjustable ventilator casing comprising a wall box, a base box, a radiator-inclosure on the base box, and an intake air-duct secured at one end to the base box and having resilient outwardly-extending lips on its opposite end for yielding adjustable engagement with the inner side portions of the wall box to conform to the cross-sectional dimensions of the box.

3. A ventilator casing comprising a base box composed of a front wall and a rear wall, and two end walls connected to the front and rear walls, each end wall being composed of two approximately equal parts detachably secured together and having a circular aperture in its upper portion; a radiator-inclosure upon the base box, and an intake air-duct detachably connected with the rear wall of the base box.

4. A ventilator casing comprising a base box with an inlet-opening in its front, a damper hinged at its bottom to the inside of the base box below the inlet-opening and having a wrist-pin on one end thereof, a radiator inclosure connected to the base box and having a sight-opening in the front wall thereof distant from the base box, an indicator plate having one side thereof pivoted to the front wall on one side of the sight-opening, and a controlling rod connected to the opposite side of the indicator plate and also to the wrist-pin of the damper.

5. A ventilating casing comprising a base box for a radiator having sections with connecting bosses, the box being composed of a rear section consisting of a rear wall and two rear end portions, the end portions being receivable between the radiator sections and having semi-circular recesses to receive the rearward portions of the connecting bosses, and a front wall and two forward end portions, the forward end portions being counterparts of the rear end portions reversely arranged and insertible between the radiator sections to the rear end portions and having semi-circular recesses to receive the forward portions of the connecting bosses, each forward end portion being detachably secured to the adjacent rear end portion of the base box.

6. A ventilator casing comprising a base box composed of a rear wall and rear end portions, the rear wall having an aperture therein and also a flange on its rear side extending about the aperture, the box being composed also of a front wall and forward end portions, the forward end portions being detachably secured to the rear end portions; each two adjacent end portions having each a semi-circular recess, the two recesses forming a circular aperture, the front wall having a doorway therein, an intake air-duct secured to said flange, a back damper hinged to the inside of the rear wall of the base box at the bottom of the aperture and operable in the air-duct, an ear secured to the damper, a fulcrum-arm secured to the rear wall below the aperture, a lever pivoted between its ends to the fulcrum-arm, a link connected to said ear and to the fulcrum-arm, a front damper hinged to the inside of the front wall of the box at the bottom of the doorway, and a link connected to the fulcrum-arm and the front damper.

7. In a ventilator casing, the combination of a rectangular wall box, a base box having an aperture in the rear wall thereof, the rear wall of the box having a flange thereon extending about the aperture, and an intake air-duct comprising a bottom and a top and also end walls, one open end of the air-duct being inserted in and secured to said flange, the opposite end of the air-duct being inserted in said wall box, the bottom and top

and also the end walls of the air-duct having each an outwardly-extending resilient lip thereon that yieldingly engages the inner side of the several portions of the wall box, 5 with a radiator-inclosure upon the base box, and a damper hinged to the rear wall of the base box at the bottom of the aperture and operable in said air-duct.

8. In a ventilator casing, the combination 10 of a base box comprising a vertical front wall having an upward-facing shoulder on the outer side thereof, a rear wall with an aperture therein above its bottom and having a flange on the outer side of the wall 15 extending about the aperture, two separate end walls each comprising two separate counterpart sections detachably secured together, one section of each end wall being detachably secured to said front wall, the remaining section being detachably secured to said rear wall, each of said end wall sections having an upward-facing shoulder on its upper outer portion, the portion of each end wall section that is adjacent to the remaining section of the end wall having a concave recess therein adjacent to and below the shoulder of the section to form a circular aperture; an air-duct detachably secured to said flange and an inclosure for radiator 20 sections comprising a rear wall seated on the said flange and having two rearwardly-extending flanges, a front wall seated on the shoulder of said front base box wall, and two end walls seated on the shoulders of the 25 sections of said end walls of the base box and connected to the front wall and also detachably connected to the flanges respectively of the rear wall of the inclosure.

9. In a ventilator casing, the combination 30

with a base box, of a radiator-inclosure 40 seated on the box and comprising a vertical back wall having two vertical flanges extending rearwardly from its opposite vertical edges respectively, a front wall, two end walls integral with the front wall and extending to and beyond the back wall and against the vertical flanges respectively, bolts securing the end walls to said flanges, a guide bar secured horizontally to the inside of the back wall, and a guide bar secured 45 horizontally to the inside of the front wall. 50

10. In a ventilator casing, the combination of a base box comprising a front wall and a rear wall and also two end walls, the rear wall extending upward beyond the plane of 55 the top of the remaining walls and having an aperture therein and also a flange on its outside extending about the aperture, each of said end walls being composed of two approximately equal parts secured together 60 on a vertical plane; and a radiator-inclosure comprising a back wall having a recess receiving the upper portion of said flange, the back wall of the radiator-inclosure being secured to the rear wall of said box, a front 65 wall secured to the front wall of the box, and two end walls connected to the front and rear walls of the radiator-inclosure and secured to the end walls respectively of the box. 70

In testimony whereof, we affix our signatures in presence of two witnesses.
